US00D607499S

(12) United States Design Patent
Tortoiali Ricci et al.

(10) Patent No.: US D607,499 S
(45) Date of Patent: * Jan. 5, 2010

(54) TYPE FONT

(75) Inventors: Marco Tortoiali Ricci, Perugia (IT);
Francesco Gubbiotti, Perugia (IT);
Tommaso Pucci, Perugia (IT)

(73) Assignee: Albini & Fontanot S.p.A., Cerasolo
Ausa (RN) (IT)

() Term: 14 Years

(21) Appl. No.: 29/333,802

(22) Filed: Mar. 16, 2009

(51) LOC (9) Cl. 18-03

(52) U.S. Cl. D18/24

(58) Field of Classification Search D18/24-33;
101/398-399

See application file for complete search history.
